(57) **CLAIM**

The ornamental design of a purse, as shown and described.

DESCRIPTION

FIG. 1 is a perspective view of a purse.

FIG. 2 is a front elevational view thereof;

FIG. 3 is a rear elevational view thereof;

FIG. 4 is an end elevational view of one end thereof;

FIG. 5 is an end elevational view of the other end thereof;

FIG. 6 is a top plan view thereof;

FIG. 7 is a bottom plan view thereof; and,

FIG. 8 is an elevational front view of the purse shown with the environmental structure of a hand to demonstrate how the purse is used.

The broken lines in the drawings form no part of the claimed design.
